UNITED STATES PATENT OFFICE

GEORGE THOMAS IRWIN, OF TORONTO, ONTARIO, CANADA

LOCKING DEVICE

Application filed February 2, 1928, Serial No. 251,421, and in Canada March 4, 1927.

My invention relates to improvements in locking devices, and the object of the invention is to devise a locking device particularly adaptable to lamps of the candelabra type and other devices in which a standard and base are incorporated, in which the locking device for locking the standard and base is hidden from view so that it cannot be interfered with and the standard inadvertently loosened in the base so that it will not retain its true vertical position, and yet which at the same time may be quickly assembled and disassembled whenever necessary without any disturbing noise, and it consists essentially of the arrangement and construction of parts as hereinafter more particularly explained.

Fig. 1 is a vertical sectional view through a base and the standard supported in the base and my locking connection between the standard and base.

Fig. 2 is an inverted plan view of the parts shown in Figure 1.

Fig. 3 is an enlarged vertical section through the central portion of the base showing the lower end of the standard, a receiving socket and locking key in elevation.

In the drawing like characters of reference indicate corresponding parts in each figure.

1 indicates the base of a device such as a candelabra lamp, crucifix, mass card holder or other similar device.

2 is a standard which is in the form of a pole and which is supported centrally in the base. The central portion of the base is provided with an orifice 1^x surrounding which on the lower face of the base is an annular flange 1°, the downwardly directed face of which is of ratchet formation as indicated at 3. Extending upwardly from the base and also surrounding the orifice 1^x is a sleeve bearing 4 provided at its upper end with an annular bearing face 4^x corresponding in diameter to the diameter of the orifice 1^x.

5 is a socket in which the lower end of the standard pole 2 is received, being secured therein by securing screws 5^x.

7 and 8 are loops depending from the socket 5 and depending below the surface

formed by the ratchet 3 as clearly indicated in Figure 1.

9 is a wedge key which is preferably secured by a chain 10 to the base 1.

The upper end of the socket 5 is provided with an annular flange 5° which when the socket is in position rests upon the top of the sleeve bearing 4, the upper portion of the socket fitting within the annular bearing face 4^x and the lower portion within the orifice 1^x thereby holding the socket in a true vertical position.

When it is desired to secure the socket in place the key 9 is passed through the loops 7 and 8 so as to bear against the ratchet surface 3, and when forced manually longitudinally to a fairly tight position the socket is turned by the operator manually gripping the key so as to force the ends of the key up the inclined surfaces of the ratchet 3 and thereby draw the standard downward and the flange 5° into tight engagement with the upper end of the sleeve bearing 4 so as to securely lock the parts in place by the frictional contact of a key 9 with the ratchet surface 3 and thereby preventing the standard pole being turned inadvertently from a position above the base.

It will be understood that devices such as I have described used at funerals must be such as can be operated quickly and noiselessly, and yet which will positively prevent the inadvertent turning of the standard pole by any unauthorized person handling the same.

Hitherto standard poles of this type have been connected to the base by means of a threaded engagement and which permitted of the standard pole being turned in the base by any onlooker at the funeral so that it will become loosened and assume an inclined position in the base presenting a very unsightly and disorderly appearance, or by a pin which loosely held the pole in the base so that it never assumed a true vertical position.

My device provides very simple means whereby this defect is overcome, insuring that the standard will be securely locked in the base by means which is invisible to the ordinary observer, and which therefore will

not be interfered with so that the standard will become loosened and which may be assembled and disassembled quickly without noise.

What I claim as my invention is:—

In a locking device, a base member provided with a cylindrical vertical bearing open at both ends, an annular ratchet extending around the lower opening of the bearing, a cylindrical member fitting in the bearing and turnable therein and provided with an enlarged portion at its upper end engaging the upper end of the bearing, loop members formed integral with the cylindrical member and extending downwardly through the lower open end of the bearing, a wedge key extending through the loop portion and bearing adjacent each end against the aforesaid ratchet surfaces so that when the cylindrical member is turned within the bearing the key ends will be carried circumferentially into wedging contact with the aforesaid ratchet surfaces.

GEORGE THOMAS IRWIN.
